(57) **CLAIM**

The ornamental design for an outer tail light portion, as shown and described.

DESCRIPTION

FIG. 1 is a front left elevated perspective view of an outer tail light portion for a vehicle;
FIG. 2 is a front left perspective view thereof;
FIG. 3 is a rear right elevated perspective view thereof;
FIG. 4 is a rear right perspective view thereof;
FIG. 5 is a front view thereof;
FIG. 6 is a rear view thereof;
FIG. 7 is a left side view thereof;
FIG. 8 is a right side view thereof;
FIG. 9 is a top view thereof;
FIG. 10 is a bottom view thereof; and,
FIG. 11 is another front view thereof, mounted on a vehicle to shown environmental structure.

The broken lines shown in FIG. 11 illustrate the environmental structure of the outer tail light portion in which the design is embodied that forms no part of the claimed design.
